DESIGN FOR A HEAD SCARF

Beatrice B. Smith and Eleanor Z. Cauter,
New York, N. Y.

Application August 12, 1944, Serial No. 114,861

Term of patent 3½ years

(Cl. D3—13)

To all whom it may concern:

Be it known that we, Beatrice B. Smith and Eleanor Z. Cauter, both citizens of the United States of America and both residing at New York city, in the county and State of New York, have invented a new, original, and ornamental Design for a Head Scarf, of which the following is a specification, reference being had to the accompanying drawing, forming a part thereof.

Fig. 1 is a plan view of a head scarf, showing our new design.

Fig. 2 is a side view of the scarf as worn on the head.

The dominant feature of the design resides in the portions shown in full lines.

We claim:

The ornamental design for a head scarf, substantially as shown and described.

BEATRICE B. SMITH.
ELEANOR Z. CAUTER.
